DESIGN FOR A CABINET FOR A GAME APPARATUS

Samuel H. Gensburg, Chicago, Ill., assignor to Chicago Coin Machine Mfg. Co., Chicago, Ill., a copartnership composed of Samuel Gensburg, Dora Gensburg, Samuel Wolberg and Eva Wolberg

Application October 30, 1941, Serial No. 103,958

Term of patent 14 years

To all whom it may concern:

Be it known that I, Samuel H. Gensburg, a citizen of the United States and a resident of Chicago, in the county of Cook and State of Illinois, have invented a new, original, and ornamental Design for a Cabinet for a Game Apparatus, of which the following is a specification, reference being had to the accompanying drawing, forming a part thereof, and in which:

Fig. 1 is a side elevational view of a cabinet for a game apparatus showing my new design;

Fig. 2 is a top plan view of the same as seen from above in Fig. 1 and at a slightly smaller scale with respect thereto; and

Fig. 3 is a front elevational view of the same likewise on a slightly smaller scale.

I claim:

The ornamental design for a cabinet for a game apparatus, as shown.

SAMUEL H. GENSBURG.
